UNITED STATES PATENT OFFICE.

CHARLES O. MYERS, OF BOILING SPRINGS, PENNSYLVANIA.

CAR-COUPING.

SPECIFICATION forming part of Letters Patent No. 498,675, dated May 30, 1893.

Application filed February 15, 1893. Serial No. 462,433. (No model.)

To all whom it may concern:

Be it known that I, CHARLES O. MYERS, a citizen of the United States, residing at Boiling Springs, in the county of Cumberland and

5 State of Pennsylvania, have invented certain new and useful Improvements in Car-Couplings, of which the following is a specification.

This invention relates to an improvement in car couplings of the pin-and-link type, and 10 the special features herein set forth, are designed as improvements on the device described in the patent granted to me January 6, 1885, and numbered 310,535.

The invention is illustrated in the accompanying drawings, in which—

Figure 1, is a vertical section through my coupler. Fig. 2, is a top plan of the same, and Fig. 3, is a front elevation.

This coupler uses two links and two pins.

20 Referring to the drawings, the letter, A, designates parts of the car-body to which the draw-head is applied; B, the movable draw-head having the flaring mouth shown at, C. The said draw-head has a recessed shank, to

25 receive the compression spring, h, which abuts at one end against the closed end, B', and at the other end against the sliding follower, H, which it presses forward against the end of the coupling-link, D, which is secured by the

30 permanent rear pin, W. The outer face of the follower has a recess, h', adapted to receive the rear end of the link, D, and press the same firmly against the pin, W, thus holding the inner end of the said link from tilting 35 up, and consequently preventing the outer end from tilting down, so that it may register with the draw-head of the other car, when the two are brought together.

The link, D, is not designed in operation to 40 be freed from the coupler by withdrawing the pin, W, but always remains secured to the same draw-head, and is only released therefrom when it is desired to change the link.

The forward end of the link, D, is engaged 45 by an uncoupling pin in the connected draw-

head of the other car, corresponding to the uncoupling pin, F, shown, which engages the link D', of said draw-head indicated by broken lines.

The operation of the levers, G; springs, k, 50 and pin, F, are detailed in my former patent above referred to, but in the present instance I have added the rod, G', which co-acts with these parts, and enables one to operate the uncoupling pin, F, from the top of the car if desired. 55

Secured to the rear end of the draw-head is the yoke, N, through which the rod M, passes centrally, being secured at its ends. Compression springs, m, are mounted on said rod 60 and abut at the forward end against the transverse bar, n, which is secured rigidly to the car, and at the rear end to the block, n', which is movable with the draw-head. These springs are designed to relieve the car of the strain of 65 any sudden jerk or pull which may be given on the coupler.

Having thus described my invention, I claim as new and desire to secure by Letters Patent—

70 In a car-coupling comprising two over-lapping coupling-links, the combination of the draw-head having two coupling-pin holes—one in front of the other; the front coupling pin, F, for engagement with a link of the opposite draw-head; a rear coupling-pin W permanently engaging an end of the other coupling-link; a compression spring within the draw-head, and a sliding follower actuated by the said spring, and having in its front face a 75 recess, h, always in engagement with the end of that coupling-link which the rear coupling pin, W, engages, substantially as described. 80

In testimony whereof I affix my signature in the presence of two witnesses.

CHARLES O. MYERS.
